UNITED STATES PATENT OFFICE.

WILLIAM R. PARK, OF TAUNTON, MASSACHUSETTS; WILLIAM R. PARK, JR., EXECUTOR
OF SAID WILLIAM R. PARK, DECEASED.

HYDROCARBON BURNER.

Application filed November 17, 1920. Serial No. 424,643.

To all whom it may concern:

Be it known that I, WILLIAM R. PARK, a citizen of the United States of America, and resident of Taunton, in the county of Bristol 5 and State of Massachusetts, have invented new and useful Improvements in Hydrocarbon Burners, of which the following is a specification.

My invention relates to hydrocarbon burners, and consists of an improvement upon hydrocarbon burners of the character described in Letters Patent of the United States No. 248,110, granted to me and Frank D. Heath on the eleventh day of October, 1881. The 15 object of my improvement is to perfect and complete the combustion of hydrocarbon fuel with air, and thus to increase the efficiency of the burner.

Hydrocarbon burners of the character indicated are adapted to burn heavy hydrocarbons, such as residues from the distillation of light oils from either asphalt-base or paraffine-base petroleum, and are generally used to burn fuel of this nature in and for steam 25 boiler furnaces. The efficiency of such a burner—as measured, for instance, by the quantity of water evaporated in a boiler per pound of hydrocarbon fuel burned—depends on the completeness with which the fuel is 30 chemically combined with the oxygen of the air supplied for combustion purposes. In burners of the character indicated, the hydrocarbon fuel is entrained into a combining tube by the inductive action of a jet of steam, 35 which also draws into and propels through the combining tube a stream of air which, though insufficient in volume to supply the oxygen required for complete combustion of the hydrocarbon fuel, primes the hydrocarbon 40 and assists in breaking it up into small drops, producing with the impelling steam-jet, a spray of mingled air steam and hydrocarbon. This spray, being ignited as it issues 45 from the combining tube, requires a large supplementary supply of air for combustion, such as was provided for by the structure and mode of operation of the hydrocarbon burner described in the above mentioned patent. The object, in the design and operation of 50 such burners, has been to introduce the supplementary air supply to the burning fuel-spray in such manner as to mingle air and fuel intimately. The attempt to effect this object, by the burner shown in the aforesaid 55 patent, involved directing the air as it en-

tered the combustion tube, so that it impinged centripetally against the fuel-spray jet, the idea being to break up the spray with air. While burners having that peculiarity, and a structural arrangement of the induct 60 end of the combustion chamber adapted to produce an impingement of air against the fuel-spray, have been found practicable, nevertheless the presence of smoke in the boiler uptake betrayed the presence of unconsumed 65 carbon, and a failure to attain complete or ideal combustion efficiency.

By a series of experiments with burners of this general type, varied in design, proportions, shape of parts, and adjustments, I have 70 become convinced that impingement of the air drawn into the combustion chamber against the fuel-spray, involved an error in theory, and produced a defect in practice. The result of these investigations is exemplified by the hydrocarbon burner illustrated 75 in the accompanying drawing, which embodies my present invention and improvement. This drawing shows the burner in vertical longitudinal section, and in part in 80 side elevation.

In the drawing, 1 represents the air priming tube, 2 the steam tube, into which steam enters through apertures 3, from the steam supply pipe 4. The hydrocarbon fuel flows 85 from the tube 5 into the space 5^a surrounding the steam tube 2 and is inducted by the steam jet into the combining tube 6, where steam, air and fuel meet, and from which they are ejected in mixture into the combustion tube 9. The supplementary and final supply of 90 air enters at 10 between the combustion tube 9 and the jacket 8, reversing its direction of flow to enter the combustion tube, into which this air is drawn by the entraining action of 95 the fuel spray, which is ignited as it issues from the combining tube 6.

At the intake end of the combustion tube 9, there is secured the intake ring 7, which is conoidal and inwardly tapered, its shape 100 and curvature being proportioned and developed so that the delivery lip of the intake ring is tangential to lines parallel with the axis of the combining tube. Preferably also, the intake ring 7 is so placed that its entrance lip lies substantially in the same plane with the delivery end of the combining tube 6. This shape and arrangement of the intake ring causes the air supply to enter the combustion tube 9, at the delivery lip of the 110

ring in a direction substantially parallel with the axis of the combining tube, which is coincident with the axis of the combustion tube. This direction of the air inflow is indicated 5 by the dotted arrows *a a*. Thus, the air entering the combining tube does not impinge upon, or in any substantial degree constrict or impede the fuel spray. But, as the burning fuel spray proceeds toward the outlet 10 end of the combustion tube 9, the gases generated by combustion expand, and as the entrained air proceeds in the same direction, it becomes heated progressively, and therefore expands. The two streams, expanding, 15 the one outwardly and the other inwardly, are constrained to mingle intimately, while neither deviates to any substantial extent from the straight path of movement through the combustion tube. Incidentally, the walls 20 of the combustion tube, though made of thin sheet iron or steel, are protected against overheating by the air in contact with them, becoming only red hot, though the flame issuing from the combustion tube is intensely 25 hot.

I have not shown any regulating damper at the entrance 10; if desired, such regulating damper as is shown in the aforesaid patent may be supplied. The practical result 30 obtained by the above described burner structure is a smokeless flame, which is the index of complete fuel consumption. By boiler test, this fuel burner has evaporated 17½ pounds of water to one pound of hydrocarbon fuel, as against fourteen and a half pounds of water per pound of fuel with a burner having the conical intake ring (such as shown in the aforesaid patent) but otherwise of the same structure and proportions. 35 As is evident from the foregoing, a cardinal feature of the invention consists in that the intake ring curves inwardly from the wall of the combustion chamber in such manner that the discharge end of the ring is substantially parallel with said wall and spaced 40 therefrom, whereby the air is permitted to expand both outwardly and inwardly to

maintain its general direction substantially parallel with the axis of the stream.

Another important feature of the invention consists in that the air passageway through jacket 8 to the combustion tube is closed, from the combining tube so that none of the air mixes with the fuel spray until after the spray has entered the combustion chamber, whereby the fuel spray is undisturbed by cross currents and eddies before it leaves the combining tube and enters the combustion chamber in the aforesaid parallel relationship with the air.

What I claim and desire to secure by Letters Patent is:

1. A hydrocarbon burner comprising a small combining tube and a relatively large combustion tube collinearly arranged with the discharge end of the combining tube terminating at the intake end of the combustion tube, a passageway for conducting air to the intake end of the combustion tube around the end of the combining tube, said passageway being closed from the interior of the combining tube, and an intake ring in the intake end of the combustion tube, proportioned to deliver the entrained air in a direction substantially parallel with the axis of the combining tube.

2. A hydrocarbon burner comprising a small combining tube and a relatively large combustion tube collinearly arranged with the discharge end of the combining tube terminating at the intake end of the combustion tube, and an intake ring in the intake end of the combustion tube, proportioned to deliver the entrained air in a direction substantially parallel with the axis of the combining tube, the intake ring curving inwardly from the wall of the combustion chamber so that the discharge end of the ring is substantially parallel with said wall and spaced therefrom.

Signed by me at Boston, Massachusetts, this fifteenth day of November, 1920.

WILLIAM R. PARK.
